UNITED STATES PATENT OFFICE.

BENJAMIN M. WALPOLE, OF PROVIDENCE, RHODE ISLAND.

ELECTRIC FUSE OR CUT-OUT.

1,086,693.

Specification of Letters Patent. Patented Feb. 10, 1914.

Application filed April 12, 1912. Serial No. 680,311.

To all whom it may concern:

Be it known that I, BENJAMIN M. WALPOLE, a citizen of the United States, and resident of the city of Providence, in the county of Providence and State of Rhode Island, have invented certain new and useful Improvements in Electric Fuses or Cut-Outs, of which the following is a specification.

10 This invention relates to improvements in electric fuse or cut-out, and has for its object to provide a cut-out that will visibly and unmistakably indicate when the inner fuse wire has blown, and to perform this 15 indicating operation without transmitting the electric current through the casing, thereby eliminating the danger of receiving a shock at the point of indication.

A further object of my invention is to 20 provide a fusee or heat conductor of such a length that the heat in the casing has had time to subside before the fusee burns through the opening in the sheath, thus 25 eliminating the danger of the fire blowing out through this opening.

With these and other objects in view, the invention consists of certain novel features of construction, as will be more fully described and particularly pointed out in the 30 appended claims.

Of the accompanying drawings: Figure 1— is a central longitudinal sectional view through the sheath showing the main fuse wire and the auxiliary fuse wire, also showing the fusee connected to the latter wire. Fig. 2— is an enlarged end view illustrating the arrangement by which the auxiliary fuse wire is held suspended within the sheath and out of contact with the same.

40 Fig. 3— is an enlarged view of the auxiliary fuse wire showing the means by which the fusee is connected to said wire. Fig. 4— is an enlarged view showing the coils in the auxiliary fuse wire, by means of which the 45 heat is intensified at a given point therein.

Fig. 5— is an enlarged view of the cup-shaped capsule which receives the coils of the auxiliary wire, the end of the fusee and the combustible cement by which the latter 50 is connected to said wire. Fig. 6— is a detail showing the end of a casing with the

end of the auxiliary fuse wire extending through an eyelet in said casing.

Referring to the drawings, the inclosing tubular sheath 1 is preferably made of non-conducting material and is closed at its ends by perforated brass caps 2—2 which may be connected to binding posts, not shown, by means of the clips 3—3.

4 designates the fuse wire which is made 50 of any suitable soft metal adapted to melt at a given temperature, the same being connected at either end to said caps and clips.

The new feature of my invention is the provision of an auxiliary fuse wire 5 of high 60 resistance which is in practice extremely small in diameter and of material which permits it to melt only at a comparatively high temperature, much higher than that of the main fuse, this higher temperature which is 70 required to melt the auxiliary fuse wire serves to more surely ignite the fusee with which it comes in contact. In other words, as is found in practice a current of low voltage 75 may be passed through the main fuse wire 75 which would rupture or melt the same and still not provide sufficient heat or arc to ignite a fusee in contact with the same, therefore in order to insure the ignition of the fusee when the main fuse wire has ruptured 80 it is found necessary to provide means for raising the temperature sufficiently to insure the ignition of the fusee which is accomplished by my auxiliary wire of a high 85 resistance material. The ends 6—6 of this auxiliary wire are held in electric connection with the end caps 2 preferably by providing metal eyelets 7 in the side of the sheath near its end and by drawing the ends of the fuse wire through said eyelets and 90 then locking the same firmly in position by passing the end caps over the turned over ends of the fuse wire thereby binding the same firmly in position without permitting the fuse wire ends to come in contact with 95 the fiber portion of the casing. This wire is provided with a plurality of coils or layers 9 or other suitable means for concentrating or intensifying the heat at one particular point therein said coils or layers being preferably near one end of the sheath. I have 100 also provided a small cup-shaped member

or capsule 10 of any suitable material, through a hole in the button of which one end of this wire is passed to draw the coils 9 within the cup. A fusee 11 which is electrically inert, has one end passed through from the inner side of the sheath outward through a small hole 12 into which it may be cemented bringing a portion of the fuse into view where its condition may be plainly 10 observed as to whether it is blown or not. If desired a label of paper 14, or other suitable material, may be cemented or otherwise fastened over the hole 12 and the end of the fusee, so that when the fusee burns, 15 this label will become charred, or otherwise discolored, and thus indicate that the fuse has blown. The opposite end 13 of this fuse is passed into the open mouth of the capsule 10 where it is held by means of a combustible cement with which the capsule is now 20 filled. The whole casing has a filling 13 of any suitable material, being preferably in a finely divided state, such as slaked lime, or the like, which permits of the escape 25 of the vapor or gas formed upon the volatilization of the fuse link by an excessive current.

In operation the cut-out is connected to the binding posts on its base, not shown, and 30 when an excessive amount of current attempts to pass therethrough a high degree of heat is generated in the main fuse wire which melts the same and breaks the circuit. The current then in attempting to pass 35 through the auxiliary fuse wire raises the same to a very high temperature which temperature is concentrated or localized and intensified at the point where the wire is coiled, the heat there being sufficient to ignite 40 the combustible cement which will in turn ignite the fusee. This fusee may be wound in a coil or extend through nearly the whole length of the sheath so that a comparatively long period of time elapses, for 45 instance a minute or more passes after the fuse has blown, before the fusee has burned its entire length and through the indicating opening. By this it will be seen that the indicating opening remains closed until the 50 fire and smoke has died out and the pressure of generated gas is removed by passing out through the vent holes in the caps.

Another feature of my invention is that I employ an auxiliary fuse wire and arrange 55 the same within the casing so that no portion of it is exposed, and have connected an electrically inert fusee to said auxiliary wire to conduct a small chain of fire from this wire to char the indicating label without connecting 60 the electric current thereto, thereby effectually eliminating the possibility of receiving an electrical shock by handling the cut-out casing while the same is in circuit, in other words, by my improved construction

no shock can be received at the aperture 65 where the indicator extends through the outer casing or sheath.

Then again, it is found in practice that where an auxiliary fuse wire extends out into contact with the fiber casing that when 70 the fuse blows and the auxiliary wire becomes highly heated it often chars or even at times sets fire to the fiber casing, thereby in a measure practically defeating the very purpose of an inclosed fuse. To obviate this 75 difficulty I have provided an auxiliary fuse wire which is not in any way connected to the fiber casing, it leads from the end caps to the interior of the casing where the heat is intensified or localized at a point remote 80 from the casing. The indicating fusee which leads from this point to the outer casing being of a low heat carrying capacity in the form of a small fusee which in itself would be incapable of creating heat enough 85 to damage, burn or set fire to the fiber tube. In this way it will be seen that I have eliminated one of the greatest dangers of the ordinary indicating fuse where an auxiliary fuse wire leads directly to or through the 90 fiber casing.

By "fusee" I mean a piece of slow burning material adapted to conduct a small chain of fire from one point to another.

I claim:

1. An electric cut-out comprising a casing, a main and an auxiliary fuse wire passing through said casing, each adapted to melt at different relative temperatures, means for localizing the heat generated by 100 the current passing through the auxiliary wire, a fusee connected to said localizing point in the auxiliary fuse wire and leading through said casing to visibly indicate when the fuse has blown whereby a predetermined 105 period of time elapses between the fusing and the indicating.

2. An electric cut-out comprising an inclosing sheath having terminals at either end, a filling in said sheath, a main and an auxiliary fuse wire extending through said sheath both electrically connected to said terminals, a plurality of coils in said auxiliary wire for intensifying the heat at a given point in said wire, an indicating fusee 115 connected to the coils in said auxiliary fuse wire and leading out through the wall of said sheath whereby an excessive current passing through said auxiliary wire will ignite said fusee.

3. An electric cut-out comprising an inclosing sheath having terminals at either end, a filling in said sheath, a main and an auxiliary fuse wire extending through said sheath both electrically connected to said terminal, a plurality of coils in said auxiliary wire for intensifying the heat at a given point in said wire, a fusee having one

end leading out through the wall of said sheath, a receptacle for receiving and retaining said coil also the opposite end of said fusee, and cement in said receptacle for 5 binding said fuse end to said wire whereby an excessive current passing through said auxiliary wire will ignite said fusee.

In testimony whereof I affix my signature in presence of two witnesses.

BENJAMIN M. WALPOLE.
